UNITED STATES PATENT OFFICE.

EMIL NEWQUIST, OF CARLTON, MINNESOTA.

SCISSORS-GRINDING ATTACHMENT FOR SEWING-MACHINES.

SPECIFICATION forming part of Letters Patent No. 622,012, dated March 28, 1899.

Application filed December 18, 1897. Serial No. 662,412. (No model.)

To all whom it may concern:

Be it known that I, EMIL NEWQUIST, of Carlton, Carlton county, Minnesota, have invented certain Improvements in Scissors-Grinding Attachments for Sewing-Machines, of which the following is a specification.

My invention is a device for sharpening scissors, &c., adapted to be detachably secured to a sewing-machine and to be actuated by the operating-belt of the machine.

To this end my invention consists in the specific construction and combination hereinafter particularly described and claimed.

In the accompanying drawings, forming part of this specification, Figure 1 is a perspective view showing my device attached to the table of a sewing-machine, and Fig. 2 is a partial section of the machine with my device attached thereto.

20 In the drawings, A represents the table of the sewing-machine, upon which is mounted the ordinary frame 2, provided with a fly-wheel 3.

25 4 represents the operating-belt of the machine.

My improved device B consists of a block 5, preferably of wood, provided with upwardly-projecting sides 6, in which is journaled the shaft 7, carrying the emery-wheel 8, adapted to be actuated by the operating-belt 4. Upon the under side of the block 5 is secured the rubber 10 to prevent marring of the machine-table. The block 5 is formed with a groove 11 to receive one side of the spring-clamp 12, by means of which clamp my device is secured to the machine-table, as shown in the drawings. A suitable support 13 for

the scissors is secured to the block immediately in front of the emery-wheel.

In use the device is placed upon the table 40 of the machine in position for the belt 4 to engage with the groove-wheel 9, the device being secured in place by the spring-clamp 12. The belt is held against the groove-wheel 9 by means of the friction-pulley 14, mounted 45 in the arm 15, having pivotal connection with the frame of the sewing-machine. The running of the machine in the ordinary manner will cause the emery-wheel to be rotated. The scissors to be sharpened are then placed 50 against the emery-wheel, being supported by the support 13.

The great advantage of my invention over the ordinary hand-sharpener or fixed attachments will be apparent. With my construction it can be quickly and easily applied to the machine and detached as soon as used without injury to the machine.

What I claim as new, and desire to secure by Letters Patent, is—

60 A grinding attachment for sewing-machines consisting of a grinding-wheel adapted to be actuated by the machine-belt, the block or base upon which said wheel is mounted provided with a groove, and the spring-clamp 65 detachably securing said attachment to the machine-table, one side of said clamp being received by said groove.

In testimony whereof I affix my signature in presence of two witnesses.

EMIL NEWQUIST.
